PULP DEHYDRATOR

Walter E. Saxe, Alhambra, Calif., assignor to The Conveyor Company, Los Angeles, Calif., a corporation of California

Application July 15, 1939, Serial No. 284,688

14 Claims. (Cl. 34—12)

This invention relates to a pulp dehydrator. These dehydrators are used for reducing the water content of moist sand and other pulps, i. e., masses of granular material, the particles of which are associated with a liquid, usually water, either free or absorbed and held by capillary attraction.

It is an object of the invention to provide means for reducing to a desired and constant percentage the moisture content of a moving bed of pulp from an initial percentage which may or may not be constant.

It is another object of the invention to provide in a pulp dehydrator utilizing a stream of air as the drying agent, an efficient practical means for supporting the pulp while it is being subjected to the action of the drying agent.

It is another object of the invention to provide means for regulating to a nicety the percentage of moisture in the pulp processed by the dehydrator, and for maintaining that percentage during a run with a minimum of fluctuation.

It is another object of the invention to provide means for recovering and returning to the untreated pulp any particles of pulp which may have been separated and carried away from the pulp during the dehydrating process by the stream of air which acts as the drying agent, or by other means.

Other objects and advantages of the invention will be apparent from a reading of the following description and the drawings, in which:

Fig. 1 is a view of a machine embodying my invention shown in longitudinal sectional elevation.

Fig. 2 is a vertical cross-sectional view taken along the line A—A of Fig. 1.

Fig. 3 is a vertical cross-sectional view taken along the line B—B of Fig. 1.

Fig. 4 is a plan view of the machine.

The machine which I have selected to show and describe as an embodiment of my invention is a sand dehydrator adapted to receive sand from a washer in which it has been cleansed of silt, dirt, humus, and other undesirable materials. The sand from the washer (not shown) is received by a de-watering device generally indicated by the numeral 11 and therein deprived of free water. The de-watering device 11 comprises a chute 12, an endless conveyor 13, and angle-iron buckets 14 which move the sand upwardly from the chute 12 into the upper end of a discharge funnel 15. When the sand reaches the funnel 15 most of the free water carried by it has been separated by gravity and has flowed back to the conveyor intake where it is removed in any suitable manner. The funnel 15 delivers the sand to the dehydrator proper, generally designated by the numeral 16. The essential parts of the dehydrator are a horizontal platform 17, a receiving hopper 18, a conveying mechanism 19, a suction chamber 20, brushes 21, and a discharge chute 22.

The forward wall 23 of the hopper 18 is provided with a vertically adjustable gate 24 by which the thickness of the sand bed 25 may be regulated. Immediately beyond the gate 24, a compacting idling roller 26 is vertically adjustably mounted in slots 27 in vertical walls 28 which retain the sand bed laterally as it travels through the dehydrator. This compacting roller 26 is adjusted so that its lower face is substantially at a level with the lower edge of the gate 24 and serves to compact the sand bed and give it a smooth level upper surface. The roller 26 and gate 24 cooperate to perform the important function of giving the same bed a uniform and constant thickness throughout its length at any one time. Since the dehydrating agent is a stream of air which passes vertically through the sand bed, it is apparent that any variation in the thickness of the bed will cause a corresponding variation in the percentage of water removed from the pulp.

The sand bed as it passes through the dehydrator is supported by and moves slidingly over the platform 17. This platform 17 is a solid sheet of material, preferably metal, and is impervious to air. The sand bed is moved longitudinally along this platform and in sliding contact with its upper surface by the conveyor 19 which comprises two lateral chains 29 and angle-iron buckets 30 carried by and between these chains. The path of the conveyor 19 is determined by three pairs of sprocket wheels 31, 32, and 33, and comprises an upper horizontal flight 34 along which the buckets 30 ride upon the upper surface of the platform 17, and a return flight 35 which passes below the vacuum chamber 20. The pairs of sprockets 31, 32, and 33, are mounted respectively upon shafts 36, 37, and 38 which are suitably journaled on the two frame walls 39 of the machine. These frame walls 39 are supported by a frame structure 40.

The conveyor 19 is driven by the sprockets 32, the shaft 37 of which receives power from a motor 41 by means of a chain drive comprising a motor sprocket 42, sprocket chain 43, and sprocket wheel 44 mounted on the shaft 37. The platform 17 is provided with a waste drain 45 to receive and remove any surplus free water which may collect on the platform 17 near the receiving end thereof.

Between the frame walls 39, which constitute the end walls thereof, is disposed the vacuum chamber 20 immediately beneath the longitudinally central portion of the platform 17. The platform 17 constitutes the upper wall 46 of the vacuum chamber. Its end walls 47 are a portion of the frame walls 39, and it is further bounded

by two metal plates 48 each of which is shaped to present a front or rear wall 49 and a bottom wall 50. The walls 50 are inclined downwardly toward their inner adjacent edges between which is secured a collecting trap 51 in which is collected the water removed from the sand, and from which it is conducted by pipes 81 to a reservoir 82. The plates 48 are suitably secured to the under surface of the platform 17 in air-sealed relationship therewith, as indicated at 83.

Subatmospheric pressure is maintained in the vacuum chamber 20 by means of a motor driven vacuum pump 52 connected to the vacuum chamber 20 by means of two air pipes 53. The vacuum pump 52 is equipped with the customary gauge 54. The degree of vacuum may be regulated by varying the speed of a vacuum pump motor 55 or by any other suitable means. The air pipes 53 are connected at their upper ends by a cross air pipe 56 which is perforated to provide communication with the interior of the vacuum chamber 20 and which is protected by a hood 57 mounted on and between the end walls 47 for the purpose of protecting the air intake pipe 56 from flying particles of sand or other solid or liquid matter.

If desired, exhaust air from the vacuum pump 52 may be conducted to an air chamber (not shown) arranged above and in suitably effected sealing contact with the upper face of the sand bed, and in vertical alignment with the vacuum chamber 20, to provide air at superatmospheric pressure, for the purpose of increasing the velocity of the air through the sand bed.

As will be seen in Fig. 2, the platform 17 is secured to the frame plates 39. The side walls 28 for retaining the sand bed laterally are secured to and between the platform 17 at their lower edges and horizontal plates 59 at their upper edges, in spaced relationship with the frame walls 39. The plates 59 are rigidly secured to the upper edges of the frame plates 39.

One or more transverse slots or gaps 58 are provided in the platform 17 extending from one side retaining wall 28 to the other side retaining walls 28, over which the sand bed 25 must pass in its travel from the hopper 18 to the chute 22. In the drawings two such gaps 58 are shown. One or more revolving cylindrical brushes 21 are mounted in the vacuum chamber 20 between the end walls 47 thereof in bearings 60 secured to the frame plates 39. Each of these brushes comprises a hub portion 61 and bristles 62 of wire or other stiff material which are mounted in and project radially outward from the hub portion 61. The outer ends of the bristles 62 constitute a cylindrical surface 80 which contacts and slides under arcuate flanges 63 depending from the front and rear edges of the transverse gaps 58. The uppermost arcuate portion of the cylindrical surface 80 of each roller occupies one of the gaps 58 and due to its convex character projects at its center slightly above the horizontal plane of the upper surface of the platform 17.

The brushes 21 are mounted on shafts 64a and 64b which are driven by a sprocket drive as follows. The shaft 64a carries a sprocket 65 which is driven by a sprocket chain 66 from a sprocket wheel 67 on the shaft 37. The shaft 64b is driven from the shaft 64a by means of sprocket wheels 68 and 69 and a sprocket chain 70. The sprocket wheels 67, 65, 69, and 68 are all of the same diameter. As a result, the shafts 37, 64a, and 64b revolve at the same speed of rotation. Since also the pitch circle of the drive sprocket 37 is of the same diameter as that of the cylindrical

surface 80 described by the outer ends of the bristles 62, the linear speed of the bristle ends is the same as that of the linear speed of the conveyor buckets 30. The sand bed, as it leaves the solid portion of the platform 17 and passes across one of the gaps 58, is received and supported by one of the rollers 21 and is propelled forwardly at the same linear speed as that by which it is moved by the conveyor 29.

Though preferable, it is not necessary that the rollers 21 be power driven. If the shafts 64a and 64b are idling shafts, it is obvious that the sand bed, as it moves over the gaps 58, will by reason of its contact with the bristles 62, turn the rollers 21 and the roller shafts 64a and 64b.

Air is drawn downwardly through the sand bed 25, as indicated by arrows 71, to the gaps 58 and the bristles 62 into the vacuum chamber 20, and thence through the pipes 53 to the vacuum pump 52. Since the bristles 62 converge radially inwardly toward the hub portion or core 61 of the rollers 21, the particles of sand of the sand pulp are inhibited from being drawn downward through the bristles into the vacuum chamber. A few particles may become lodged between the outer ends of the bristles. As each roller 21 revolves, bringing such lodged sand particles into the vacuum chamber, they are dislodged from the bristles by a row of jets of water issuing at high pressure from suitably shaped perforations in an associated water pipe 72 and fall with the water from the jets into the collecting trap 51, whence they are led through pipes 81 to the reservoir 82. The water gathered from the sand by the air stream indicated by the arrows 71 also collects in the trap 51 and is led to the reservoir 82.

Tests of a dehydrator embodying my invention have shown that it is not necessary, except with certain sticky materials of low water content, to spray the bristles with jets of water in the manner above described. The water extracted from the sand by the air column moving through the gaps 58, gathers upon the bristles, and when the bristles are pointed downward during their return movement, this water falls therefrom carrying with it any sand particles which may have been separated from the sand bed and become lodged in the bristles.

The water level 73 in the reservoir 82 seals the vacuum chamber against air inflow through the pipes 81 and is maintained constant at the level of the overflow chute 74 by a supply pipe 75, in which the flow of water is controlled by a float valve 76 which is connected to a suitable water supply. The level 73 is sufficiently below the trap 51 to prevent the water in the reservoir 82 from being drawn upwardly to the vacuum chamber.

Water is drawn from the bottom portion of the reservoir 82, in which the sand carried from the under surface of the sand bed 25 by the bristles 62 is held in suspension, by means of a centrifugal pump 77, and returned through a pipe 78 to a sand washer (not shown). If so desired, the sand-laden water may be extracted from the bottom of the reservoir 82 by means of a bucket conveyor (not shown), and similarly returned to the sand washer.

It will be observed that the percentage of moisture extracted from the sand, and likewise the percentage of moisture remaining in the sand delivered to the chute 22 may be varied by three different regulatory adjustments. The gate 24 and compacting roller 26 may be moved vertically

to vary the depth of the sand bed. The subatmospheric pressure in the vacuum chamber 20 may be varied by regulation of the vacuum pump 52. The linear speed of travel of the conveyor 19 and the peripheral speed of the outer ends of the bristles 62 may be varied by varying the speed of the motor 41 or changing the speed ratio of the sprocket drive. Since sand of any given degree of fineness and of any other given characteristics has substantially the same moisture content when it has been deprived of the free water which it carries but has not been deprived of any of its capillary water, it follows that with any given speed of travel of the conveyor and brushes, any given depth of sand bed, and any given adjustment of the means for creating subatmospheric pressure in the vacuum chamber, the percentage of capillary water remaining in the sand when it is delivered to the chute 22 at the discharge end of the dehydrator will be constant within very narrow limits. There are industrial operations for which it is desirable that sand pulp have a uniform moisture content, among which may be mentioned the mixing of concrete or mortar. There are conditions under which other kinds of pulp should, for best results, have a uniform moisture content.

With a machine constructed substantially like that shown in the drawings, commercial tests have shown that with a sand bed twelve inches deep and three feet wide traveling at a linear speed of thirty to forty inches per minute, and with a ten inch mercury vacuum maintained in the vacuum chamber, the moisture content after removal of free water can be reduced from approximately seventeen to seven per cent in twenty-seven tons per hour. Approximately one per cent of the sand will be carried from the sand bed into the vacuum chamber on the bristles of the roller brushes and returned to the washer.

My invention is not limited to the particular embodiment shown and described herein. The dehydrator used to set forth the principles of the invention is selected for illustrative purposes only. The principles of the invention are applicable to dehydrators of many kinds and types characterized by suitability for treating a granular pulp or any other water-containing material which is air-pervious and composed of small particles relatively movable with respect to each other. My invention is to be given the scope and definition set forth in the following claims.

I claim as my invention:

1. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; and an air-pervious supporting means for said pulp bed mounted to move substantially in the plane of said platform across said gap in the direction of travel of the pulp bed and to move proximately beneath the rims of said gap, said means directly contacting the pulp of and supporting said pulp bed across said gap.

2. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below

5 said gap and communicating therewith; an air-pervious supporting means for said pulp bed mounted to move substantially in the plane of said platform across said gap in the direction of travel of the pulp bed and to move proximately beneath the rims of said gap, said means directly contacting the pulp of and supporting said pulp bed across said gap; and means for moving said air-pervious supporting means across said gap at substantially the same linear speed as the linear speed of travel of said pulp bed.

3. In a pulp dehydrator, the combination of: a stationary platform support for a moving pulp bed and having formed therein a gap across which the moving pulp bed is unsupported by said platform and which extends across the path of movement of said pulp bed; a vacuum chamber below said gap and communicating therewith; an air-pervious supporting means for said pulp bed mounted to move substantially in the plane of said platform across said gap in the direction of travel of the pulp bed and to move proximately beneath the rims of said gap, said means directly contacting the pulp of and supporting said pulp bed across said gap; and conveyor means for propelling the pulp slidably over said platform.

4. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; and a cylindrical brush having radially diverging bristles horizontally rotatably mounted in said vacuum chamber transversely of said platform on an axis substantially below the plane of said platform with the upper portion of its surface seated in said gap substantially in the plane of said platform and directly contacting the pulp of and supporting said pulp bed across said gap.

5. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; a cylindrical brush having radially diverging bristles horizontally rotatably mounted in said vacuum chamber transversely of said platform on an axis substantially below the plane of said platform with the upper portion of its surface seated in said gap substantially in the plane of said platform and directly contacting the pulp of and supporting said pulp bed across said gap; and means for rotating said brush at a speed which will impart to its peripheral surface the same linear speed as that of the said pulp bed.

6. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; an endless air-pervious supporting means for said pulp bed mounted to move across said gap substantially in the plane of said platform in the direction of travel of the pulp bed and to move prox-

mately beneath the rims of said gap and to have a return movement at a level below said gap, said means directly contacting the pulp of and supporting said pulp bed across said gap; and means for spraying cleansing fluid on said 5 air-pervious supporting means during said return movement.

7. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; and means mounted and operating within said chamber for contactually supporting and moving said pulp bed across said gap substantially in the plane of said platform.

8. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; means for supporting and moving the pulp bed across said gap substantially in the plane of said platform; and adjustable means in advance of said gap for establishing any desired constant depth of the pulp bed, comprising a vertically adjustable horizontal compacting roller mounted in vertically spaced relationship with said platform and in advance of said roller a vertically adjustable horizontally arranged gate mounted in vertically spaced relationship with said platform, the range of adjustment of the lower edge of said gate being substantially the same as the range of adjustment of said roller.

9. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; an air-pervious supporting means for said pulp bed mounted to move across said gap substantially in the plane of said platform in the direction of travel of the pulp bed and to move proximately beneath the rims of said gap, said means directly contacting the pulp of and supporting said pulp bed across said gap; a closed conduit for removing water and particles of pulp from said vacuum chamber; a settling tank at a lower level than said vacuum chamber in which is disposed the lower end of said conduit; means for maintaining a constant water level in said tank above the lower end of said conduit; and means for removing water laden with said pulp particles from the lower levels of said tank to a conduit suitable for returning said water laden with said particles to said platform.

10. In a pulp dehydrator, the combination of: a platform support for a moving pulp bed and having formed therein a gap across which the moving pulp bed is unsupported by said platform and which extends across the path of movement of said pulp bed; means for moving the pulp bed over said platform; a vacuum chamber below said gap and communicating therewith; a cylindrical brush horizontally rotatably mounted in said vacuum chamber transversely of said plat-

form with the upper portion of its surface seated in said gap substantially in the plane of said platform and directly contacting the pulp of and supporting said pulp bed across said gap, said brush comprising a core and radially diverging bristles mounted on said core; and means for spraying jets of water on said bristles at a point within said vacuum chamber.

11. In a pulp dehydrator, the combination of: a platform support for a moving pulp bed and having formed therein a gap across which the moving pulp bed is unsupported by said platform and which extends across the path of said pulp bed; means for moving the pulp bed over said platform; a vacuum chamber below said gap and communicating therewith; and an endless movable supporting means for said pulp disposed in said gap, comprising parallel arranged elongated elements with their upper ends substantially in the plane of said platform and contacting and supporting said pulp, said elements being laterally closely spaced to afford voids for the reception of liquid extracted from the pulp while excluding substantially all particles of the pulp, said supporting means having a return flight, during the movement over which said elements are inverted whereby liquid and any particles of pulp removed from the pulp bed may fall therefrom.

12. In a pulp dehydrator, the combination of: a solid platform provided with at least one air gap therethrough and thereacross; means for feeding a moistened granular material to one end of said platform in a bed; bucket means for moving said bed contactually and slidably over said platform from said feeding means; means including a suction box for drawing air through said material and said air gap; and an endless travelling air-pervious conveying means disposed with one portion of its path of travel substantially in the plane of said platform and longitudinally across said gap whereby it directly contacts and supports without relative movement said bed and having its return path in said suction box.

13. In a pulp dehydrator, the combination of: means for forming a bed of moistened granular material; means for supporting said bed; means for continuously moving said bed after it is formed, said supporting and moving means causing movement of said bed with its underface describing a surface of smooth contour; means including a suction chamber having its mouth in and across said surface and interrupting said supporting means; and an air-pervious supporting means mounted to move longitudinally of said mouth and substantially in said surface and at the speed of travel of said bed.

14. In a pulp dehydrator, the combination of: means for forming a bed of moistened granular material; means for supporting said bed; means for continuously moving said bed after it is formed, said supporting and moving means causing movement of said bed with its underface describing a surface of smooth contour; means including a suction chamber having its mouth in and across said surface and interrupting said supporting means; and a revolvable brush having radial bristles idly mounted on an axis centrally transverse of said mouth with its upper side substantially in the plane of said surface, whereby the sand-bed rotates said idly mounted brush.

CERTIFICATE OF CORRECTION.

Patent No. 2,237,635.

April 8, 1941.

WALTER E. SAXE.

It is hereby certified that error appears in the printed specification of the above numbered patent requiring correction as follows: Page 1, second column, line 17, for the word "same" read --sand--; page 4, second column, line 65, claim 14, for "mooth" read --smooth--; and that the said Letters Patent should be read with this correction therein that the same may conform to the record of the case in the Patent Office.

Signed and sealed this 13th day of May, A. D. 1941.

(Seal)

Henry Van Arsdale,
Acting Commissioner of Patents.
